DOOR CONTROLLED ELECTRIC LIGHTING SWITCH

Filed Nov. 2, 1923

2 Sheets-Sheet 2

FIG. 6.

FIG. 7.

Patented Mar. 1, 1927.

UNITED STATES PATENT OFFICE.

JOSEPH M. KERN, OF OSWEGO, NEW YORK.

DOOR-CONTROLLED ELECTRIC-LIGHTING SWITCH.

Application filed November 2, 1923. Serial No. 672,289.

This invention relates to a door-controlled switch for electric lighting circuits of the class set forth in my pending application, Serial Number 566,274 filed June 6, 1922, in which a self-closing switch is adapted to be opened by the closing of the door in combination with means operable at will for displacing the switch opening means to permit the switch to close while the door is closed.

The object of the present invention is not only to break the lighting circuit when the door is closed and permit the automatic closing of the circuit when the door is opened as in my pending application referred to, but also to utilize a part of the same switch-controlling means for closing and opening the circuit at will whether the door is opened or closed.

Other objects and uses relating to specific parts of the device will be brought out in the following description.

In the drawings:

Figure 1 is a horizontal sectional view of a portion of a door partly broken away, and adjacent stiles of the door opening showing the light-controlling switch in operative position in the stile at the opening edge of the door.

Figures 2 and 3 are enlarged horizontal sectional views of the same device taken in different horizontal planes, on lines 2-2 and 3-3, Figure 5.

Figure 4 is an inverted horizontal sectional view of the device shown in Figures 2 and 3, taken in the plane of line 4-4, Figure 5.

Figure 5 is a longitudinal vertical sectional view taken in the plane of line 5-5, Figure 2.

Figures 6 and 7 are transverse vertical sectional views taken respectively in the planes of lines 6-6 and 7-7, Figure 2 except that the commutator and ratchet wheels are shown in elevation.

Figure 8 is a longitudinal vertical sectional view of a portion of one end of the device taken in the plane of line 8-8, Figure 7.

In order that my invention may be clearly understood, I have shown a portion of a door -A- as hinged to one of the upright stiles -B- of the door opening and adapted to swing against the other opposite upright stile or jamb -B'- in which the

lighting switch is installed for automatic control by the free edge of the door.

The various parts of the switch are preferably mounted in a suitable case or housing consisting, in this instance, of bottom 60 and top walls -1- and -1', opposite side walls -2- and -2'- and end walls -3- and -3'- which are removably secured to the end edges of the bottom, top and side walls by screws -4- or equivalent fastening means shown by dotted lines in Figure 5, all of which parts except the screws, may be made of bakelite, vulcanized fiber or other suitable insulating material capable of being molded to the desired form 70 or may be made of cast or sheet metal with suitable provision for insulating the various electrical parts to prevent short circuits.

The entire case or housing is preferably inserted in a mortised opening -b- in the 75 jamb or stile -B'- with its end wall -3- substantially flush with the corresponding inner face of the jamb where it is held in place by screws -5- passing through wings or extensions -6- on the lower and upper 80 edges of the end wall -3- as shown in Figure 5.

Enclosed within the case or housing is an electric switch consisting, in this instance, of a rotary disk -7- of electric conduct- 85 ing material and a contact brush -8- preferably of spring metal tensioned to contact at one end with the upper face of the disk -7- and having its other end secured by a suitable binding post -9- to the end wall 90 -3'- of the case and adapted to be connected in an electric lighting circuit.

The disk -7- is secured by any suitable fastening means to a sleeve -10- of insulating material which in turn is rotatably mounted upon a screw spindle or stud -11- having its upper end secured to a bracket -12- projecting inwardly from the end wall -3'- as shown in Figure 5.

The disk -7- is preferably circular and 100 concentric with the axis of the sleeve -10- and pivotal bolt or screw -11- and is provided with a plurality of, in this instance four, segments -13- projecting axially across the periphery of the adjacent portion 105 of the sleeve -10- in uniformly spaced relation circumferentially to form intervening insulating spaces, and together with the inclosed part of the sleeve -10-, constitutes what may be termed a commutator.

The portion of the sleeve —10— engaged by the segments —13— is flanged and is of somewhat less axial depth than that of the segments which therefore, project slightly beyond the lower face of the flange to form contact faces for engagement by a suitable brush —14—.

The circumferential lengths of the segments —13— are somewhat less than the spaces between them so as to enable the contact end of the brush —14— to alternately register with the segments and spaces as the disk —7— is rotated step by step in a manner hereinafter described.

15 The brush —14— is preferably made of spring metal and has one end secured by a binding post —15— to the end wall —3— of the case for electrical connection with the lighting circuit and its other end extended under the lower face of the segments —13— and adjacent flange of the sleeve —10— for alternate engagement with said segments and flange as the sleeve —10— and disk —7— thereon are rotated for alternately closing and opening the lighting circuit.

20 The sleeve —10— and its commutator segments —13— are normally set to register one of the spaces with the contact end of the brush —14— when the door is closed and it therefore, follows that the lighting circuit will be normally opened to extinguish any lights which may be connected therein and that if the sleeve —10— is rotated one-eighth of a revolution, it will bring the next segment of the commutator into registration with the brush —14— to close the circuit and thus energize the lights therein. If this successive step by step rotation of the sleeve —10— is repeated, the segments —13— and spaces between them will be alternately registered with the contact end of the brush —14— and will therefore, effect a corresponding alternate opening and closing of the lighting circuit.

25 A plunger —16— is reciprocally movable along a dovetailed guide —17— on the bottom —1— of the housing and is provided with a reduced outer end —16'— of rectangular cross section projecting through a corresponding opening —17'— in the end wall —3— into the path of movement of the free edge of the door —A—, the outer end of the extension —16'— being beveled transversely to permit the free edge of the door to ride thereagainst when closed for forcing the plunger inwardly.

30 This inward movement of the plunger is utilized for opening the electric lighting switch to break the lighting circuit by the closing of the door and for this purpose the plunger is provided with a movable section —18— having one end pivoted at —19— to the plunger to permit it to swing laterally or horizontally and its other end

provided with a wedge-shaped extension —20— adapted to enter between the free end of the brush —8— and upper face of the disk —7— when the plunger is moved inwardly by the closing of the door to the 70 position shown in Figure 3, said member —18— being made of insulating material so that when wedged between the contact member —8— and disk —7— it will effectively break the lighting circuit. 75

On the other hand, when the door is opened, the plunger —16— including its pivoted member —18— will be automatically returned or retracted by means of a coil spring —21— until limited by the engagement of the larger portion of the plunger with the inner face of the end wall —3— as shown in Figure 5. 80

As previously stated, the commutator disk —7— and commutator brush —14— 85 are normally set to cause one of the spaces between the segments —13— to register with the brush —14— and inasmuch as the four segments are arranged in uniformly spaced relation circumferentially, it is evident that each one-eighth of a revolution of the sleeve —10— with the disk —7— thereon will cause the segments —13— and intervening spaces between the segments to alternately register with the contact end of 90 the commutator brush —14— thereby alternately making and breaking the electrical connection between the disk —7— and commutator brush —14— and in order that this rotary movement of the disk may be controlled by the closing and opening of the door in such manner as to assure contact between one of the segments and commutator brush when the door is opened, the sleeve —10— is provided with a four-tooth 100 ratchet wheel —22— rigid therewith and having its teeth in equally spaced relation circumferentially and adapted to be engaged by suitable pawls —23— and —23'— carried by the plunger —16— as shown 110 more clearly in Figure 4.

One of the pawls as —23— is adapted to engage the teeth of the ratchet wheel at one side of its axis as the plunger —16— is forced inwardly by the closing of the 115 door for rotating the sleeve and commutator segments one-eighth of a revolution for breaking the lighting circuit while the other pawl —23'— is adapted to engage the teeth of the ratchet on the opposite side of its 120 axis by the return movement of the plunger —16— through the medium of the retracting spring —21— when the door is opened thereby rotating the sleeve and commutator segments another one-eighth of a revolution in the same direction to restore the 125 electrical connection between the disk —7— and commutator brush —14—.

It is now clear that when the door is opened and the plunger —16— is forced to 130

- its extreme outward position by the spring —21—, electrical connection will be established between one of the segments —13— and commutator brush —14— and that when 5 the door is closed, this electrical connection between the commutator disk —7— and brush —14— will be broken but will be again restored immediately upon the opening of the door.
- 10 These results are particularly desirous as a matter of economy in the use of electric current in connection with doors leading to cellars, attics, bath rooms, garages and in other relations where there is more or less 15 liability of omitting to turn off the lights when the doors are closed from the outside of the lighted room.
- It is desirable however, to provide the same device with means whereby the lights 20 may be turned on and off independently of the operation of the door, that is, whether the door is opened or closed, and for this purpose the sleeve —10— is provided with an extra ratchet wheel —24— having eight 25 teeth in uniformly spaced relation circumferentially and adapted to be operated by a push button —25— through the medium of a pawl —26—, said push button being also provided with an inwardly projecting extension —27— adapted to engage and displace the pivoted section —18— of the plunger —16— from between the disk —7— and contact brush —8— when the door is closed.
- 30 That is, the pivoted section —18— of the plunger —16— is provided intermediate its ends with a boss —18'— which, when the door is opened and the plunger —16— is at its extreme outward movement is out of the 35 path of movement of the extension —27— of the push button —25—, but is forced into the path of movement of said extension —27— when the plunger —16— is forced inwardly by the closing of the door at which 40 time, the wedge-shaped extension —20— will be forced between the disk —7— and contact brush —8— to break the lighting circuit.
- Now, if it is desired to restore the light 45 while the door is closed, it is simply necessary to push the button —25— inwardly which will cause the extension —27— to engage the boss —18'— and thereby displace the wedge-shaped extension —20— from between the disk —7— and contact brush —8— wholly to one side of the brush thus 55 permitting the brush to establish electrical connection with the disk —7—, it being understood that when the door is closed, the space between the segments —13— will be registered with the commutator brush —14—.
- This inward movement of the plunger —25— together with its extension —27— and pawl —26— not only causes the exten-
- sion —27— to displace the wedge-shaped extension —20— from between the disk —7— and brush —8— but also causes the pawl —26— to rotate the ratchet wheel —24— one tooth space or one-eighth of a turn which will cause one of the segments —13— to contact with the commutator brush —14— thereby closing the lighting circuit and energizing the electric lamps.
- As soon as these electric connections have been established by the operation of the push button —25—, the latter may be released and returned by a retracting spring —28—, Figure 4, the ratchet wheels being prevented from backward rotation or excessive forward rotation by means of a detent —29— which is secured to the end wall —3— and is spring pressed against the periphery of the ratchet wheel —24— as shown in Figure 4.
- 80 A retracting spring —30— is secured to the plunger —16— and is spring pressed against one edge of the pivoted section —18— as shown in Figure 3, for returning the pivoted section —18— to its normal position after being displaced by the operation of the push button —25— and its extension —27— and when the plunger —16— is returned by the action of the spring —21— 85 when the door is opened.
- 85 The push button —25— is guided in a hollow boss —31— projecting outwardly from the side —2— of the case or housing and through a suitable opening —b'— in the corresponding side of the door casing —B'— 90 preferably facing the room in which the lights to be controlled are located.
- The hollow boss —31— is preferably made 95 separate from the side wall —2— of the housing to permit it to be secured in position 100 after the main body of the housing has been inserted in the opening —b— to avoid excessive mutilation of the door jamb or casing —B'— but is rigidly secured to the side wall —2— by clamping bolts —32—, Figure 105 3.
- The inner portion of the push button —25— is preferably flattened and elongated vertically at —25'— to fit in a corresponding opening in the hollow boss —31— to prevent turning of the push button and parts carried thereby, and also to form a stop for engaging the outer wall of the boss and thereby limiting the outward movement of the push button by its retracting spring —28—, as shown in Figure 6, said retracting spring being secured to the inner face 110 of the side wall —2— by any suitable fastening means as a screw —33—, Figure 4.
- 115 120 125

Operation.

Assuming that the door is in its normal closed position to force the plunger —16— inwardly against the action of the spring —21—, Figure 3, in which case one of the

spaces between the commutator segments —13— will be registered with the commutator brush —14—, and that the wedge-shaped extension —20— of the section —18— of the plungers —16— has been forced between the disk —7— and switch brush —8— thereby breaking the lighting circuit for extinguishing the lights which may be connected therein; then a person opening the door to enter the room in which the lamps are located would permit the plunger —16— to be forced outwardly by its retracting spring —21— thereby causing the pawl —23— to rotate the ratchet wheel —22— one tooth space or one-eighth of a turn to bring one of the segments —13— into electrical contact with the commutator brush —14— for closing the lighting circuit and energizing the lamps.

Now, if the door should be closed either purposely or by accident while the person is still in the room in which the lights are located, it would of course, force the plunger —16— inwardly and cause the pawl —23— to engage and rotate the ratchet wheel —22— one-eighth of a turn which would cause the registration of one of the spaces between the segments with the commutator brush —14— and thereby break the lighting circuit and extinguish the lights, and if it should be desired to leave the door closed and to re-energize the lamps, it would be simply necessary to push the button —25— inwardly thereby causing the extension —27— to displace the wedge —20— from between the disk —7— and switch brush —8— to re-establish electrical connection between those parts and would also cause the pawl —26— to engage and rotate the ratchet wheel —24— one tooth space to bring the next succeeding segments —13— into electrical contact with the commutator brush —14— thereby closing the lighting circuit and again energizing the lamps after which the push button —25— may be allowed to return to its normal position by its retracting spring —28— leaving the wedge extension —20— in engagement with the edge of the switch brush —8— which is then in electrical contact with the disk —7— to complete the closing of the circuit.

On the other hand, if the door should remain open while the person is in the room in which the lights are located and it is desired to extinguish the lights, it may be accomplished by simply pushing the button —25— inwardly to rotate the ratchet sleeve —10— and disk —7— carried thereby, one-eighth of a turn through the medium of the pawl —26— and ratchet wheel —24— which would bring one of the spaces between the

segments into registration with the commutator brush —14— for breaking the lighting circuit.

It is now clear from the foregoing description and the accompanying drawings that by alternately pushing the button —25— inwardly after each return, the lighting circuit may be opened and closed at will, whether the door is opened or closed and that no matter how many times the push button has been forced inwardly in either position of the door, the closing of the door will automatically break the lighting circuit in case it should be closed, while on the other hand, the lighting circuit will always be closed and the lights energized by the opening of the door.

It is evident, however, that various changes may be made in the detail construction and arrangement of the various parts of the device without departing from the spirit of this invention, and therefore, I do not wish to limit myself to the precise construction shown and described.

I claim:

1. In a door-controlled electric lighting switch, a rotary conducting member having contact segments in uniformly spaced relation, a ratchet wheel having a number of teeth corresponding to the number of the segments and operatively connected to the conducting member to rotate therewith, a self-retracting plunger actuated in one direction by the closing of the door and in the opposite direction when the door is opened, pawls carried by the plunger for engaging the ratchet teeth and rotating the conducting member one-half tooth space at a time, each forward and return movement of the plunger and the contact brush for the segments, said brush and contact member being electrically connected in the lighting circuit, and additional means operable at will for rotating said contact member step by step independently of the movements of the plunger.

2. In a door-controlled electric lighting switch, a rotary conducting member having contact segments in uniformly spaced relation circumferentially, brushes contacting respectively with said member and with the segments and connected in the lighting circuit, means operable at will for rotating the contact members step by step to alternately register its segments and spaces with one of the brushes and means actuated by the closing of the door for breaking contact between the other brush and the conducting member.

In witness whereof I have hereunto set my hand this 27th day of October, 1923.

JOSEPH M. KERN.
